US00D506456S

(12) **United States Design Patent** (10) Patent No.: **US D506,456 S**
Shindo (45) Date of Patent: **** Jun. 21, 2005**

(54) **DISC PLAYER**

(75) Inventor: **Koji Shindo**, Tokyo (JP)

(73) Assignee: **Sony Corporation**, Tokyo (JP)

(**) Term: **14 Years**

(21) Appl. No.: **29/200,449**

(22) Filed: **Mar. 1, 2004**

(51) LOC (8) Cl. **14-01**

(52) U.S. Cl. **D14/156**

(58) Field of Search **D14/135-136, D14/156-157, 160-165, 167-168, 192-198, 188, 217, 257, 258, 445; 360/99.02, 99.07; 369/75.11, 75.21, 77.21, 77.11; 720/612, 619, 647, 655; 455/344, 347-351**
